US00D885415S

(12) **United States Design Patent** (10) **Patent No.:** **US D885,415 S**
Deng (45) **Date of Patent:** **** May 26, 2020**

(54) **DISPLAY SCREEN OR A PORTION THEREOF WITH GRAPHICAL USER INTERFACE**

(71) Applicant: **LENOVO (BEIJING) CO., LTD.**, Beijing (CN)

(72) Inventor: **Yuanyuan Deng**, Beijing (CN)

(73) Assignee: **Lenovo (Beijing) Co., Ltd.**, Beijing (CN)

(**) Term: **15 Years**

(21) Appl. No.: **29/652,007**

(22) Filed: **Oct. 1, 2018**

Related U.S. Application Data

(62) Division of application No. 29/616,324, filed on Sep. 5, 2017, now Pat. No. Des. 833,457.

(30) **Foreign Application Priority Data**

CLAIM

The ornamental design for a display screen or a portion thereof with graphical user interface, as shown and described.

DESCRIPTION

FIG. 1 is a front view of a display screen or a portion thereof with graphical user interface showing the new design; and, FIG. 2 is a front view showing a second embodiment thereof.

The outermost solid-line perimeter illustrates a display screen or portion thereof.

The broken lines illustrate portions of a graphical user interface and form no part of the claimed design.
